M. J. Bissell

UNITED STATES PATENT OFFICE.

GEORGE R. PARR, OF WEST ORANGE, NEW JERSEY.

MEANS FOR REDUCING VIBRATION OF CENTRIFUGALS.

Application filed August 23, 1921. Serial No. 494,588.

To all whom it may concern:

Be it known that I, GEORGE R. PARR, a citizen of the United States, residing at 3 Ridgefield Avenue, West Orange, New Jersey, have invented new and useful Improvements in Means for Reducing Vibration of Centrifugals, of which the following is a specification.

My invention relates to means for reducing the vibration of centrifugals, and particularly to means for reducing the vibration of a centrifugal drying drum in a clothes washing machine.

One of the objects of my invention is to provide a vibration reducing mechanism which can be cheaply and readily manufactured and applied to existing machines or can be built as a part of the machine when the machine is being constructed, and which can be easily replaced or repaired.

With the above and other objects in view my invention consists in the parts, improvements and combinations more fully pointed out hereinafter.

25 Turning now to the drawings:

Fig. 1 is a front elevation partly in section, showing one embodiment of my invention applied to the centrifugal dryer of a clothes washing machine of any desired type;

Fig. 2 is a sectional detail of the device;

Fig. 3 is a plan view of the structure shown in Fig. 2; and

Fig. 4 shows another embodiment of the invention.

The clothes washing machine shown in Fig. 1 has the frame 1 upon which a stationary tub or container 2 is mounted and in which a centrifugal drying drum 3 is located, all as usual.

In the form of the washing machine shown in Fig. 1, the centrifugal drying drum which is perforated, is provided with means for rotating it, which may consist of an electric motor 4, belt 5, pulleys 6 and 7, the latter being mounted in a bracket 8 and driving the shaft 9 of the centrifugal drying drum thru friction disks 10 and 11. These disks drive the drum at a speed depending on their position with relation to each other.

A treadle 12, lever 13 is connected to the shaft 9 by a connection 14. By pressing upon the pedal the drum is whirled, the water escapes thru the perforations in the drum and the clothes are dried. The above machine is one of a number of well known forms

in common use. When such a drum is loaded with clothes to be dried, it frequently happens that the uneven distribution of the load throws the drum out of balance so that when the drum is whirled at a drying speed, usually hundreds of turns a minute, there is a tendency to set up oscillations of the drum.

In accordance with my invention, I provide a plurality of rollers or shoes which are independently mounted and which may be placed so as to cooperate with the inner surface of the drum and which are so constructed that they will check the vibration or reduce its development. These rollers are carried by a non-rotating part of the machine, as for example, by the casing. This casing may be the stationary tub or the cover.

As illustrated in Fig. 1, I secure to the frame of the machine and preferably to the outer surface of the fixed tub, a number of brackets 15. I may use three or four brackets equally spaced about the fixed frame. Upon each bracket there is mounted an arm, the distal end of which carries a roller or shoe. In the form illustrated the roller 16 is carried by the hinged arm and a spring 17 yieldingly draws the roller outwardly. The mounting of each roller carrying arm is independent so that each roller may be separately adjusted in position and each roller may exert its action upon the drum, without interference by the other roller.

The roller or shoe is adapted to contact with a part of the inner surface of the drum. In the best embodiment of the invention, the roller contacts with a track on the inner surface and in the particular form of the invention illustrated the roller contacts with the inner surface of the rim of the drum, the rim consisting of a bead or lip 18 running around the inside of the throat of the drum at its mouth. I make the face of the roller concave as at 19 so that it may hug the lip.

The hinged arm may be constructed in various ways. In the form illustrated the arm consists of two parts 20, 21, the outer part sliding on the inner and being correctly guided by the pin and slot connection 22, 23. The spring 17 may be attached to a post 24 at one end and to the post 25 at the other, thus pulling the roller toward the track.

The hinges 26 of the arms are arranged horizontally so that the arms may be thrown up and outwardly in order to disengage the

roller from the track. When not in use the arms with the rollers will hang down as shown in Fig. 1. The cover 27 is preferably slotted at 28 to permit the arm to enter the 5 machine. The cover is ordinarily made removable.

As illustrated in Fig. 4, the rollers are carried by the cover, which forms part of the casing of the machine, and which may 10 be hinged to the frame, or the cover may be removable and replaceable on the frame, the cover when replaced thus forming part of the casing. Each roller 29 (a number are used equally spaced about the inside of the 15 cover) is mounted on a two-part member or arm; the two parts 30 and 31 having a sliding fit as shown in Fig. 1. The outer part 31 is secured to the cover 32 which may be hinged at 33. A spring 34 pulls the roller 20 29 toward the rim of the cover. The roller 29 is concaved at 34 and rounded off at 35. The concave fits the ring and the rounded portion enables the rollers to slip over the rim when the cover is lowered down upon 25 the machine. The man hole 36 permits one to adjust the rollers into contact with the rim, if desired.

Having thus described the invention, its 30 operation will be clear. After taking off or raising the cover, loading and if necessary raising the centrifugal drum, but before starting it in rotation, the hinged arms with their rollers, in the form shown in Fig. 1, are turned inwardly of the machine and 35 the rollers brought into contact with the inner face of the rim of the drum. Or in the form shown in Fig. 4, the cover carrying the rollers is lowered upon the machine, and the rollers snap in place. The drum 40 is then rotated. The vibration is checked by the rollers which tend to centralize the drum. If the drum has a tendency to oscillate toward one side, the rollers will bring it back toward central position or prevent the 45 action. A plurality of rollers equally spaced about the drum are used.

What I claim as new and desire to secure by Letters Patent is:

1. The combination of a rotating cylindrical drum, of means for reducing the vibration thereof, comprising a plurality of members spaced about the drum, each mounted independently of the other, means for securing each member to the machine and a roller 50 carried by each member, said roller being arranged to project within the drum and to contact with a part of the inner surface of the drum, thus reducing vibration.

2. The combination of a rotating cylindrical drum, of means for reducing the vibration thereof, comprising a plurality of members spaced about the drum each mounted independently of the other, means for securing each member to the casing of the 60 machine and a roller carried by each mem-

ber, said roller being arranged to project within the drum and to contact with a part of the inner surface of the drum, thus reducing vibration.

3. The combination of a rotating cylindrical drum, of means for reducing the vibration thereof, comprising a plurality of members spaced about the drum, each mounted independently of the other, means for securing each member to the casing of the machine and a spring-pressed roller carried by each member, said roller being arranged to project within the drum and to contact with a part of the inner surface 70 of the drum, thus reducing vibration.

4. The combination of a rotating cylindrical drum, of means for reducing the vibration thereof, comprising a plurality of arms spaced about the drum, each mounted independently of the other, means for securing each arm to the casing of the machine and a spring-pressed roller carried by each arm, said roller being arranged to project within the drum and to contact with a part 80 of the inner surface of the drum, thus reducing vibration.

5. The combination of a rotating cylindrical drum, of means for reducing the vibration thereof, comprising a plurality of arms equally spaced about the drum, means for pivotally securing each arm to the casing of the machine, each arm being independently mounted, a roller carried by the distal end of each arm, and a spring for each roller, said roller being arranged to contact with a part of the inner surface of the drum, thus reducing vibration.

6. The combination of a rotating cylindrical drum, of means for reducing the vibration thereof, comprising a plurality of arms equally spaced about the drum, means for hinging each arm to the casing of the machine, each arm being independently hinged, a roller carried by the distal end of each arm, means permitting said roller to move radially, and a spring urging said roller outwardly, said roller being arranged to contact with the inner surface of the rim of the drum.

7. The combination of a rotating cylindrical drum, of means for reducing the vibration thereof, comprising a plurality of arms equally spaced about the drum, means for hinging each arm to the casing of the machine, each arm being independently hinged, a concave roller carried by the distal end of each arm, means permitting said roller to move radially upon said arm, a spring urging said roller outwardly, said roller being arranged to contact with the inner surface of the rim of the drum.

8. The combination of a rotating cylindrical drum, of means for reducing the vibration thereof, comprising a plurality of arms equally spaced about the drum, means

- for hinging each arm to the frame of the machine, each arm being independently hinged, said hinges being arranged horizontally so as to permit the arms to be raised and lowered, a roller carried by the distal end of each arm, a 20 spring urging said roller outwardly, said roller being arranged to contact with a track on the inner surface of the drum.
- 5 10. The combination of a rotating cylindrical drum, of means for reducing the vibration thereof, comprising a plurality of arms spaced about the drum, means for securing each arm to the casing of the machine and a spring-pressed roller carried by each arm, said roller being arranged to 25 30 contact with a part of the inner surface of the drum, thus reducing vibration.
- 10 15. 9. The combination of a rotating cylindrical drum, of means for reducing the vibration thereof, comprising a plurality of arms equally spaced about the drum, each arm comprising two members, one sliding with respect to the other, means for hinging each arm to the frame of the machine, each arm being independently hinged, said hinges being arranged horizontally so as to permit

the arms to be raised and lowered, a roller carried by the distal end of each arm, a 20 spring urging said roller outwardly, said roller being arranged to contact with a track on the inner surface of the drum.

10. The combination of a rotating cylindrical drum, of means for reducing the vibration thereof, comprising a plurality of arms spaced about the drum, means for securing each arm to the casing of the machine and a spring-pressed roller carried by each arm, said roller being arranged to 25 30 contact with a part of the inner surface of the drum, thus reducing vibration.

In testimony whereof, I have signed my name to this specification.

GEORGE R. PARR.
